UNITED STATES PATENT OFFICE

2,327,417

RUNNER FOR ROAD SCRAPERS

Edward C. Gledhill, Galion, Ohio

Application May 8, 1942, Serial No. 442,251

3 Claims. (Cl. 37—150)

This invention relates to road scrapers and more particularly to an open runner scraper of that general class shown and described in my prior United States Patent No. 2,215,830, the present invention being an improvement thereon.

The object of the invention is to provide a road shaper having a scraping blade, the front cutting edge of which is so disposed with respect to the adjacent opening in the runner that, as the machine travels over a roadbed, the material at one side of the roadbed will be carried through the opening in the runner toward the opposite side of said roadbed.

A further object of the invention is to provide an open runner and scraping blade assembly especially designed for use as a left hand runner but which, if desired, may be used as a right hand open runner.

A further object is to provide a scraping blade having a terminal angularly disposed scraping lip which serves to gather loose surface material on the outside of the runner and deliver said material through the open runner to the opposite side of the machine, thereby materially increasing the effective scraping area of the machine and, consequently, the efficiency thereof.

A still further object of the invention is generally to improve this class of machines so as to increase their utility, durability and efficiency.

In the accompanying drawing:

Figure 1 is a side elevation of a left hand open runner showing the same in position on a road scraper.

Figure 2 is a longitudinal sectional view of the runner and scraping blade assembly, taken on the line 2—2 of Figure 1.

Figure 3 is a detail perspective view of the forward end of the scraping blade and its associated parts.

The improved device forming the subject matter of the present invention comprises a supporting frame 5, to the lower portion of which are rigidly secured front and rear longitudinally disposed runner sections 6 and 7, said runner sections being of different lengths and spaced apart to form an intermediate opening 8 through which the surface material of a roadbed is caused to pass from one side of the roadbed to the other as the machine travels thereover. Disposed at the forward end of the long runner section 7 and arranged at an incline or angle with respect to the longitudinal plane of said runner is a scraping blade 9, the front end of which projects laterally beyond the outer side of the runner 7 and

is provided with an angularly disposed scraping lip 10 which serves to gather loose material on the outside of the runner and deliver said material through the opening 8, to the opposite side of the machine, thereby increasing the effective scraping area of said machine. The lower portion of the blade 9 is provided with a sharpened scraping edge 11 which merges into a similar scraping edge 12 formed on the lip 10.

Riveted or otherwise rigidly secured to the rear face of the scraping blade 9 is a right angle bar 13 and welded or otherwise secured to the upper web of the bar 13 is a similar right angle bar 14. The scraping blade 9 is provided with a vertical extension or plate 15 which serves to confine the loose surface material in contact with the forward face of the scraping blade and prevent said loose material from being carried rearwardly between the right and left hand runners of the scraping machine. The forward end of the extension or plate 15 is bent rearwardly, at 16, and secured to the adjacent portion of the angle iron 14 to form a closure and also to reinforce and strengthen the device. A vertical guide post 17 is secured to the frame 5, near the forward end of the runner section 7, said guide post having a cylindrical sleeve 18 connected with the blade assembly and provided with a threaded nut 19 adapted to receive a correspondingly threaded adjusting rod 20. The upper end of the threaded adjusting rod 20 is provided with a universal joint 21 operatively connected with an operating shaft 22 extending to a point adjacent the driver's seat and provided with a hand wheel 23, by rotating which the scraping blade assembly may be adjusted vertically to permit a shallow or deep cut, or a leveling of the surface of the roadbed.

Secured to the angle bar 14 is a rearwardly extending brace 24 comprising integral converging arms connected at their point of intersection with a straight brace or plate 25, which latter brace is also secured to the bar 14. The braces 24 and 25 not only serve to reinforce and strengthen the scraping blade assembly but also serve to house and protect the adjusting mechanism for the scraping blade. It will thus be seen that as the scraping lip 10 projects laterally beyond the runner section 7, when the machine is caused to travel over a roadbed, said lip will gather loose material on the left hand side of the machine and deliver same to the scraping blade 9 and be guided by said scraping blade to the right hand side of the machine. It will further be noted that by operating the hand

wheel 23, the scraping assembly may be raised or lowered to meet the requirements of various road conditions.

While the open runner is particularly designed for use as a left hand runner, it will be understood that by reversing the position or angularity of the scraping blade, said left hand runner may be used with equally good results as a right hand open runner.

From the foregoing description it is thought that the construction and operation of the device will be readily understood by those skilled in the art and further description is deemed unnecessary.

Having thus described the invention, what is claimed is:

1. A road machine including a frame, a runner carried by the frame and including front and rear sections spaced apart to form an opening, a scraping blade mounted on the runner at the opening therein and provided with an angularly disposed gathering lip, a vertical extension on said scraping blade, an angle bar secured to the scraping blade, at said extension, a substantially V-shaped brace secured to the angle bar, a straight brace connecting the angle bar and said V-shaped brace, a vertical post disposed within the V of said brace, a sleeve on the post connected with the blade assembly and provided with a nut, a threaded rod engaging the nut, and means connected with the threaded rod for rotating the same to raise and lower the scraping blade, said V-shaped brace forming a shield for the sleeve and nut.

2. In a road machine, a frame, a runner carried by the frame and including front and rear sections spaced apart to form an opening, a scraping blade mounted on the runner at the opening therein and having one end thereof projecting laterally beyond the adjacent side of the runner and provided with a gathering lip, an angle bar secured to the rear of the scraping blade, a vertical extension plate secured to the scraping blade and having one end thereof bent

laterally and secured to the angle bar to form a closure, a brace having converging arms secured to said angle bar, an intermediate brace connecting the converging arms at the intersection thereof with said angle bar and forming compartments, a vertical guide post mounted on the frame and extending through one of the compartments for attachment to the runner, a sleeve on the guide post connected with the blade assembly and provided with a nut also disposed within said compartment, a threaded rod engaging the nut, and means operatively connected with the threaded rod for rotating same to raise and lower the scraping blade.

3. In a road machine, a frame, a runner carried by the frame and including front and rear sections of different lengths spaced apart to form an opening, an inclined scraping blade mounted on the runner at the opening therein and having one end thereof projecting laterally beyond the outer side of said runner and bent to form a longitudinally disposed gathering lip, a right angle bar secured to the rear face of the scraping blade, a second right angle bar secured to the first mentioned bar, a vertical extension plate mounted on the scraping blade and provided with a laterally bent portion secured to one of said right angle bars, an outwardly bowed brace having converging arms secured to the last mentioned angle bar, an intermediate brace forming a connection between said angle bar and the arms at the intersection thereof, said scraping blade and gathering lip being provided with a cutting edge, a vertical guide post carried by the frame and arranged between the arms of the brace, a sleeve on said guide post connected with the blade assembly and provided with a threaded nut, a threaded rod engaging the nut, and means operatively connected with the threaded rod for rotating same to raise and lower the scraping blade and gathering lip, the converging arms of the brace serving to house and protect the sleeve and threaded nut.

EDWARD C. GLEDHILL.
